(57) **CLAIM**

I claim the ornamental design for a soft bag for waist attachment, as shown and described.

DESCRIPTION

FIG. 1 is a perspective view of a soft bag for waist attachment, illustrated in a closed position and in-use as worn by a person, showing my new design;

FIG. 2 is a perspective view thereof;

FIG. 3 is a front elevational view thereof;

FIG. 4 is a right-side elevational view thereof, the left-side elevational view being a mirror image thereof;

FIG. 5 is a top plan view thereof;

FIG. 6 is a bottom plan view thereof;

FIG. 7 is a rear elevational view thereof; and,

FIG. 8 is a front elevational view thereof, illustrated in an open position.

The strap is shown broken away in FIGS. 2-3 and 5-7 to indicate indeterminate length.

The broken lines showing a woman in FIG. 1 are included for the purpose of illustrating the invention in use, and form no part of the claimed design. The broken lines in FIG. 8 represent stitching.
